[57] CLAIM

The ornamental design for an hourglass timer, as shown.

DESCRIPTION

FIG. 1 is a perspective view of an hourglass timer showing my new design;

FIG. 2 is a top plan view thereof, the bottom plan view being a mirror image thereof;

FIG. 3 is a typical side elevational view thereof.

A broken-line showings of the sand level in FIGS. 1 and 3 are for environmental purposes and form no part of the claimed design.

FIG.1

FIG.2

FIG.3
